United States Patent Office

Des. 182,784

Patented May 20, 1958

182,784

WEATHERSTRIPPING UNIT

Joseph C. Bancroft, Jamestown, N. Y.

Application February 5, 1957, Serial No. 44,764

Term of patent 14 years

(Cl. D13—6)

FIG.1.

FIG.2.

FIG.3.

FIG.4.

FIG.5.

Fig. 1 is a side elevational view of a weatherstripping unit embodying my new design;

Fig. 2 is a top plan view of the same;

Fig. 3 is a bottom view of the same;

Fig. 4 is an end view of the same; and

Fig. 5 is a perspective view of the same.

I claim:

The ornamental design for a weatherstripping unit, substantially as shown.
